IMPROVEMENT IN LATCH MEANS FOR COLLAPSING TAPS

Royce M. Strickland, New Haven, Conn., assignor to Greenfield Tap and Die Corporation, Greenfield, Mass., a corporation of Massachusetts

Application February 16, 1953, Serial No. 337,012

3 Claims. (Cl. 10—145)

This invention relates generally to taps of the tapered thread-cutting type, and more particularly to power-operated and self-collapsing taps of this type.

A prior self-collapsing power tap of this type is shown and described in the patent to Breitenstein, No. 2,135,067, dated November 1, 1938. This prior tap has a carrier for a plurality of tapered thread-cutting chasers which are radially moved into and from cutting engagement with work by means of cams on an axially movable operating plunger in the carrier. The operating plunger, which is normally spring-urged into a retired position in which the chasers are collapsed out of cutting engagement with work, is connected for joint axial movement with a latch that is normally yieldingly urged radially outwardly into locking engagement with the adjacent end face of a ring on the carrier when the plunger is advanced into its operating position in which the cams thereof hold the chasers in thread-cutting engagement with work. Axially slidably on the ring is a tripping member having an inclined surface which cooperates with a similar inclined surface on the latch to cam the latter radially inwardly out of locking engagement with the ring and release the operating plunger for spring-return to its retired position when the advance of the tripping member is stopped prior to the termination of the usual advance movement of the chasers into the axially immovable work. Provisions are also made in this prior tap to retract the chasers, prior to the conclusion of a thread-cutting operation, to such a slight extent that they will for the brief remainder of their thread-cutting operation perform on the work with a relatively fine finish cut, and thus prevent the formation of highly objectionable shoulders on the thread when the chasers are suddenly retracted therefrom on spring-return of the operating plunger into its retired position. To this end, an outer portion of the locking surface of the latch is inclined to the adjacent end face of the ring so that the operating plunger will, during the inward camming of the latch out of locking engagement with the ring and prior to the release of the latch from the latter, be spring-returned from its normal operating position to such a slight extent as to bring about the aforementioned finish-cutting performance of the chasers for the brief remainder of their thread-cutting operation. Since for efficiency and other reasons only a small fraction of the time allotted for a thread-cutting operation of the chasers is reserved for their finish-cut performance, the latch is cammed out of locking engagement with the ring during a correspondingly small part of the normal advance motion of the chasers for a thread-cutting performance, wherefore the locking surface of the latch is necessarily of small width radially of the ring, and its inclined portion is even of smaller width. It is this small width of the inclined portion of the locking surface of the latch which is responsible for occasional malfunctioning of the tap in the important respect of the finish-cut of the chasers toward the end of a thread-cutting operation. Thus, it happens occasionally with fairly new

taps, and more frequently with older taps, that the narrow inclined portion of the locking surface of the latch jumps from interlock with the adjacent end face of the ring under conditions of disturbance such as even slight vibration or shock, aided and abetted by the tendency of the spring force on the operating plunger to draw the inclined surface portion of the latch out of locking engagement with the ring. This tendency of the latch to jump prematurely from interlock with the ring is even enhanced by an unduly limited contact area between the inclined surface portion of the latch and the adjacent end face of the ring. Thus, the latch has a part-circular periphery which fits in the ring and is drawn thereinto when the latch is released from interlock therewith and the operating plunger is spring-returned to its retired position. Accordingly, the inclined portion of the locking surface of the latch, which is formed by a bevelled outer edge of the latter, has only a line contact with the adjacent end face of the ring when riding on the same and, hence, offers little resistance to disturbing forces which tend to jump the latch from interlock with the ring. Moreover, the line contact between the bevelled edge of the latch and the adjacent end face of the ring results in early and excessive wear of a very small local area of the latch which is the very area thereof that cooperates with the ring in controlling the slight spring-return of the operating plunger from its normal operating position for the achievement of the brief finish-cut performance of the chasers toward the end of their thread-cutting operation. Early and excessive wear of the latch at this critical contact area further enhances the chances of malfunctioning of the tap and leaves much desired in the way of accurate control over the brief finish-cut performance of the chasers.

It is the primary aim and object of the present invention to provide a self-collapsing power tap of this type which has none of the deficiencies of the aforementioned tap.

Thus, it is among the objects of the present invention to provide a tap of this type with a latch which will perform the same functions of locking the operating plunger in its operating position against spring-return into its retired position during the greater part of a thread-cutting operation of the chasers and permitting slight spring-return of the operating plunger toward the end of a thread-cutting operation for the brief finish-cut performance of the chasers, yet which will fail to jump from interlock with the ring under any circumstances and will show little wear even after long use.

It is another object of the present invention to interpose the latch as a connecting link between the operating plunger and an aligned spring-urged retract plunger in such wise that the latch is axially movable with the retract plunger and has a cam connection with the operating plunger for slightly retracting the latter from its normal operating position for a finish-cut performance of the chasers when the latch is cammed from interlock with the ring, permitting thereby a non-bevelled formation of the locking surface of the latch which affords a very substantial contact area between the latch and the adjacent end face of the ring with optimum locking performance throughout the cam-out of the latch from interlock with the ring, and consequently subjecting the locking surface of the latch to little wear and assuring secure interlock between latch and ring until the former is by cam action released from the latter.

It is a further object of the present invention to provide the cooperating cam faces of the aforementioned cam connection between the latch and operating plunger with considerable contact areas, thereby to reduce wear of these cam faces to a minimum and facilitate their formation, as well as obtain a most accurate control over

the slight retraction of the chasers from the work for their brief finish-cut performance on the latter toward the end of a thread-cutting operation.

Further objects and advantages will appear to those skilled in the art from the following, considered in conjunction with the accompanying drawings.

In the accompanying drawings, in which certain modes of carrying out the present invention are shown for illustrative purposes:

Fig. 1 is a side view, partly in section, of a self-collapsing power tap embodying the present invention;

Fig. 2 is a fragmentary longitudinal section through the same tap;

Fig. 3 is a section taken on the line 3-3 of Fig. 2;

Figs. 4 and 5 are longitudinal sectional views, partly in elevation, of the tap in different operating conditions of the same;

Fig. 6 is a longitudinal section through the tap in still another operating condition of the same;

Fig. 7 is another longitudinal section through the tap, taken substantially on the line 7-7 of Fig. 4;

Figs. 8 and 9 are cross-sections through the tap, taken substantially on the lines 8-8 and 9-9, respectively, of Fig. 4;

Fig. 10 is a longitudinal section through a part of the tap;

Fig. 11 is a cross-section through a part of the tap, showing a slightly modified version of the latter; and

Fig. 12 is an enlarged fragmentary section through work which has been threaded with the present tap.

Referring to the drawings, and more particularly to Figs. 1 to 7 thereof, the reference numeral 20 designates a self-collapsing power tap having a carrier 22 which at its front is centrally recessed at 24 and there provided with a plurality of equi-angularly spaced radial guideways 26, in this instance four, for the reception of chasers 28 for cutting tapered threads. The chasers 28 are held in their respective guideways 26 in the carrier 22 for axial movement with the latter by means of a retainer disc 30. Slidably interlocked with the inner ends of the chasers 28 in the fashion shown in Figs. 2 and 3 are cams or wedges 32 on the forward end of an operating member or plunger 34 which is axially slidable in a central bore 36 in the carrier 22. Thus, the chasers 28 will be moved outwardly into cutting engagement with work W on sliding the operating plunger 34 in the direction of the arrow 38 in Fig. 2, and the chasers will be moved inwardly out of cutting engagement with the work on sliding the plunger in the opposite direction.

The carrier 22 is cylindrical and carries on its periphery an axially slidable sleeve 40 which through a transverse key 42 is operatively connected with a spring-urged plunger 44 in the central bore 36 in the carrier 22. The key 42, which is releasably secured in the plunger 44 by the threaded end 46 of a rod 48, extends through an elongated slot 50 in the carrier 22 and is fittedly received with its ends in diametrically opposite slots 52, respectively, in the sleeve 40 (Figs. 4, 5 and 7). The sleeve 40 may be considered a head of the spring-urged plunger 44, and both, head and plunger, are held non-rotatable relative to the carrier 22 by the key 42. The plunger head 40 is intermediate its ends provided with a part-peripheral groove 54 having a semi-cylindrical bottom 56 merging tangentially into diametrically opposite flats 58 in the plunger head (Figs. 4, 5, 7 and 8). Form-fitted in the part-peripheral groove 54 in the plunger head 40 and guided therein for radial movement is a latch 60 of open ring shape (Figs. 4 and 8), having an end face 62 which, during a thread-cutting operation of the chasers 28, is adapted to be in locking engagement with a stop shoulder 64 that is formed by the adjacent end face of the cylindrical rim 66 of a cup element 68 on the carrier 22. Compression-type springs 70, received in sockets 72 in the latch 60 and bearing against the cylindrical bottom 56 of the part-peripheral groove 54 in the plunger

head 40, normally urge the latch 60 into the locking position shown in Figs. 2 and 4 in which a relatively narrow marginal portion of its end face 62 is in locking engagement with a portion of the adjacent end face 64 of the rim 66 of the cup element 68 on the carrier. The cup element 68 is threadedly received with its bottom 74 on the carrier 22 for axial adjustment thereon.

The earlier mentioned rod 48, which is threaded with one end into the plunger 44, extends rearwardly into an enlarged central bore 78 in a shank portion 80 of the carrier 22 (Figs. 1 and 6) and is surrounded by a compression spring 82 which is interposed between a head 84 on the rod 48 and a washer 86 seated against an annular shoulder 88 in the carrier. The spring 82 normally urges the plunger 44 and its head 40 into the retract position shown in Fig. 6 in which the plunger head 40 rests against the bottom 74 of the cup element 68 on the carrier. The plunger head 40 assumes its retract position when the chasers 28 are retracted from work W (Fig. 6), as will be explained more fully hereinafter. On the other hand, the chasers 28 will be in thread-cutting engagement with the work W when the plunger head 40 assumes the advance position shown in Fig. 4 in which the latch 60 is locked to the stop shoulder 64 to prevent the spring-return of the plunger head into its retract position during the thread-cutting operation of the chasers.

A coupling 90, to be described more fully hereinafter, is provided between the latch 60 and the operating plunger 34 to connect them for joint axial movement. The plunger head 40 is received with a sliding fit in the rim 66 of the cup element 68 (Fig. 4), and the form-fitting latch 60 must, for its release from the stop shoulder 64, be depressed into the part-peripheral groove 54 in the plunger head 40 to the extent indicated in Fig. 5 before the latch will permit the spring-return of the plunger head into its retract position (Fig. 6). Longitudinally slidably on the plunger head 40 and on the rim 66 of the cup element 68 is a sleeve 92 which has a spline connection 94 with the plunger head 40 so as to be nonrotatable thereon (Fig. 9). The spline connection 94 comprises in this instance a key 96 on the plunger head 40 (Figs. 4 and 5), and a longitudinal groove 98 in the sleeve 92 (Fig. 9) in which the key 96 is slidably received. The sleeve 92 is provided with an internal frusto-conical cam surface 100 which is adapted to cooperate with a similar frusto-conical cam surface 102 of the latch 60 in camming the latter from its locking position (Fig. 4) into its release position (Fig. 5) on relative axial movement of the plunger head 40 and sleeve 92, as will be readily understood.

When the present tap 20 is idle, the plunger head 40 is normally in its retract position (Fig. 6) in which the chasers 28 are fully retracted from work. To set the tap for a thread-cutting operation, the plunger head 40 is shifted, against the force of its return spring 82, into the advance position shown in Fig. 4 in which the latch 60 will automatically become locked to the stop shoulder 64 and the chasers 28 are projected outwardly for a thread-cutting operation. To shift the plunger head 40 from its retract position into its advance position, there is provided a resetting lever or handle 104 which is pivoted in the sleeve 92 and has a ball-shaped end 106 received in a socket-like opening 108 in the carrier 22 (Figs. 2 and 6). More particularly, the resetting handle 104 has an intermediate ball-shaped portion 110 which is substantially fittedly received in an opening 112 in the sleeve 92 and mounted on a pivot pin 114 in the latter. To reset the tap for a thread-cutting operation, the handle 104 is turned counterclockwise from the idle position in Fig. 6 into the reset position in Fig. 4, moving thereby the sleeve 92 axially forwardly relative to the carrier 22. Since the sleeve 92 bears normally against an annular shoulder 116 on the plunger head 40 (Fig. 6), it stands to reason that the plunger head is also moved forwardly by the sleeve.

92 when the handle 104 is turned to its reset position (Fig. 4) in which the plunger head is sufficiently advanced to permit the latch 60 to snap into locking engagement with the stop shoulder 64.

Usually, a tap of this type is axially moved with its chasers into the work W to be threaded and the work is turned during the thread-cutting operation, although it is apparent that either the tap or the work may be rotated as well as moved axially, or the tap may be rotated and the work moved axially, for a thread-cutting operation. For its usual axial movement for a thread-cutting operation, the tap 20 is mounted with the shank portion 80 of its carrier 22 in the turret 118 of a screw machine or in any other suitable holder. For a thread-cutting operation on work W, the tap 20 is reset, as described, by means of the handle 104 while the chasers 28 are outside the work. Thereupon, the tap is advanced with its chasers 28 into the rotating work, and the chasers will start to cut a thread substantially when the tap reaches in its forward travel the position shown in Fig. 4. The chasers 28 will during the continued forward travel of the tap from the position in Fig. 4 cut more and more of the tapered thread *t* in the work, as will be readily understood. Somewhat prior to the conclusion of a thread-cutting operation of the chasers 28, the front face 120 of the sleeve 92 moves into engagement with any suitable fixed stop 122 and is held axially immovable thereby while the carrier 22 and the plunger head 40 with its latch 60 continue to move forwardly for the brief remainder of the thread-cutting operation. It is during this brief continued forward travel of these parts relative to the stopped sleeve 92 that the cam surface 100 of the latter cooperates with the cam surface 102 of the latch 60 in camming the latter from locking engagement with the stop shoulder 64 (Fig. 5) and permitting spring-return of the plunger head 40 into its retract position (Fig. 6) for full retraction of the chasers 28 from the finished thread *t* in the work prior to the axial retraction of the tap from the work.

To limit rearward movement of the sleeve 92 on the plunger head 40 and cup element 68 so that the ball end 105 of the resetting handle 104 will in no event be turned out of register with the socket-like opening 108 in the carrier 22, the sleeve 92 receives a stud 126 (Fig. 10) having a shank 128 which projects into a longitudinal groove 130 in the plunger head 40. The effective travel range of the shank 128 in the groove 130 may be regulated by an adjustment screw 132 in the plunger head 40. The screw 132 is readily accessible for adjustment purposes through aligned holes 134 and 136 in the cup element 68 and plunger head 40, respectively. The sleeve 92 is also provided with a peripheral groove 138 for use with a shifter fork for tap-resetting purposes, in which case the resetting handle 104 may be removed from the tap and a filler plug 140 mounted in the opening 112 in the sleeve 92 by means of the same pin 114 which serves as a pivot pin for the resetting handle 104 (Fig. 11).

The previously mentioned coupling 90 comprises a transverse key 142 (Fig. 7) which is releasably retained in the operating plunger 34 by the conical tip of a spring-urged plunger 144 and extends through and beyond the elongated slot 50 in the carrier 22 and aligned slots 146 in the plunger head 40. The opposite follower ends 148 of the key 142 extend into opposite cam slots 150, respectively, in the latch 60 (Figs. 4, 5 and 7). The cam slots 150 are inclined to the longitudinal axis of the carrier 22, wherefore these cam slots will, during the radial cam-out of the latch 60 from locking engagement with the stop shoulder 64, cooperate with the follower ends 148 of the key 142 in slightly retracting the operating plunger 34 from the chasers 28. Such slight retraction of the operating plunger 34 during the cam-out of the latch 60 from locking engagement with the stop shoulder 64 will result in slight retraction of the chasers 28 from the work to such a desired extent that the chasers will during the

brief remainder of their thread-cutting operation perform with an increasingly finer cut on the work and thereby avoid the formation of highly objectionable shoulders *s* on the thread *t* (Fig. 12) which would be formed if the chasers would at the end of their thread-cutting operation be suddenly retracted from the work without previously changing their cut from normal to finer. Of course, the chasers 28 will be conditioned for their normal-cut performance when the tap is, after retraction from the threaded work, reset for the next thread-cutting operation (Figs. 2 and 4). Thus, the coupling 90 serves not only to impart the axial motion of the plunger head 40 and its latch 60 to the operating plunger 34, but serves also to achieve a change in cut of the chasers on the work from normal to finer at the end of their thread-cutting operation to prevent the formation of highly objectionable shoulders on the finished thread.

The non-bevelled formation of the locking surface 62 of the latch 60 in a plane at right angles to the axis of the tap affords a maximum contact area between the latch and the stop shoulder 64 with optimum locking performance throughout the cam-out of the latch from locking engagement with the stop shoulder, subjects the locking surface of the latch and the stop shoulder to only negligible wear over a long period of use, and assuredly prevents jumping of the latch from locking engagement with the stop shoulder under all circumstances. Further, the follower ends 148 of the key 142 are preferably provided with opposite cam surfaces 152 of considerable surface area which are in uniform engagement with the inclined sides 154 of their receiving cam slots 150 in the latch 60 (Figs. 4 and 5). Also, the cam slots 150 in the latch 60 and the follower ends 148 of the key 142 may be made of considerable width for adequate strength of the key as a safe motion transmitter between latch and operating plunger. Of course, the considerable dimensions of the cam slots 150 in the latch and of the follower ends 148 of the motion-transmitting key 142 facilitate the accurate machining of these parts, reduce wear of the cam slots and registering follower ends of the key to a minimum, and afford a most accurate control over the slight retraction of the chasers from the work for their brief finish-cut performance on the latter toward the end of a thread-cutting operation.

The invention may be carried out in other specific ways than those herein set forth without departing from the spirit and essential characteristics of the invention, and the present embodiments are, therefore, to be considered in all respects as illustrative and not restrictive, and all changes coming within the meaning of equivalency range of the appended claims are intended to be embraced therein.

What is claimed is:

1. In a collapsible tap having a centrally recessed and longitudinally slotted carrier provided with an external stop shoulder and substantially radial guideways for a plurality of chasers, and an operating member axially movable in said carrier recess for moving said chasers, the combination of a spring-urged plunger movable axially of said carrier and having a longitudinally slotted head slideable on the outer periphery of said carrier and provided with an outer peripheral groove; an open-ring latch received in said peripheral groove in the plunger head and guided therein for radial movement; a coupling between said latch and member for their joint axial movement, said latch being normally yieldingly urged radially into locking engagement with said shoulder to hold said plunger against spring-return from an advance position into a retract position in which said member holds said chasers in and out of cutting engagement with work, respectively; and means for depressing said latch radially out of locking engagement with said shoulder, said coupling being formed by a transverse key in said member extending through said slots in said carrier and plunger head and having opposite follower ends, and opposite cam

slots in said open-ring latch receiving said follower ends, respectively, and cooperating therewith, on depression of said latch out of locking engagement with said shoulder, to move said member axially for slight retraction of said chasers from a normal cut to a finer cut on work.

2. The combination in a collapsible tap as set forth in claim 1, in which said cam slots in said open-ring latch are straight slots inclined to the carrier axis, and said follower ends of said key have similarly inclined opposite faces in uniform engagement with the walls of said inclined slots.

3. In a collapsible tap having a centrally recessed and longitudinally slotted carrier provided with substantially radial guideways for a plurality of chasers, a cup element on said carrier having a cylindrical rim spaced outwardly from the latter and provided with an end face which serves as a stop shoulder, and an operating member axially movable in said carrier recess for moving said chasers, the combination of a spring-urged plunger movable axially of said carrier and having a longitudinally slotted head received with a sliding fit in said cylindrical rim, said plunger head having intermediate its ends diametrically opposite flats and a part-peripheral groove the ends of the bottom of which are formed by said flats; an open ring latch form-fitting in said part-peripheral groove in said plunger head and guided therein for radial movement; a coupling between said latch and member for their joint axial movement,

said latch being normally yieldingly urged radially outwardly into locking engagement with said stop shoulder to hold said plunger against spring-return from an advance position into a retract position in which said member holds said chasers in and out of cutting engagement with work, respectively; and means for depressing said latch radially inwardly out of locking engagement with said stop shoulder and into form-fitting relation with said part-peripheral groove to permit spring-return of said plunger into its retract position in which said latch is within said cylindrical rim of said cup element, said coupling being formed by a transverse key in said member extending through said slots in said carrier and plunger head and having opposite follower ends, and opposite cam slots in said open-ring latch receiving said follower ends, respectively, and cooperating therewith, on depression of said latch out of locking engagement with said stop shoulder, to move said member axially for slight retraction of said chasers from a normal cut to a finer cut on work.
